(57) **CLAIM**

The ornamental design for a motorcycle headlight, as shown and described.

DESCRIPTION

FIG. 1 is a perspective view of a motorcycle headlight showing my new design;

FIG. 2 is a side elevational view thereof, the opposite side elevational view being a mirror image; and,

FIG. 3 is a front elevational view thereof.

The broken line showing of the circle on the top boss is for illustrative purposes only and forms no part of the claimed invention.
